Patented Oct. 3, 1961

191,437

PORTABLE SERVICE STATION ISLAND UNIT

Charles E. Knox, Jr., 1007 Slocum St., Dallas, Tex.

Filed Dec. 12, 1958, Ser. No. 53,756

Term of patent 14 years

(Cl. D13—1)

Fig. 1

Fig. 2

Fig. 3

Fig. 4

Fig. 5

FIGURE 1 is a front elevational view of a portable service station island unit embodying my new design;

FIGURE 2 is a rear elevation view thereof;

FIGURE 3 is a top plan view thereof;

FIGURE 4 is a side elevational view thereof taken from the left of FIGURE 1; and

FIGURE 5 is a side elevational view thereof taken from the right of FIGURE 1 with portions in broken lines omitted for convenience of illustration.

The dominant feature of my design resides in portions shown in full lines on the drawings.

I claim:

The ornamental design for a portable service station island unit, substantially as shown and described.
